(57) **CLAIM**

What is claimed is the ornamental design for a motorcycle ignition coil assembly, as shown and described.

DESCRIPTION

FIG. 1 is a perspective view a motorcycle ignition coil assembly showing a new design;

FIG. 2 is a front view of the motorcycle ignition coil assembly of FIG. 1;

FIG. 3 is a rear view of the motorcycle ignition coil assembly of FIG. 1;

FIG. 4 is a top view of the motorcycle ignition coil assembly of FIG. 1;

FIG. 5 is a bottom view of the motorcycle ignition coil assembly of FIG. 1;

FIG. 6 is a right side view of the motorcycle ignition coil assembly of FIG. 1; and,

FIG. 7 is a left side view of the motorcycle ignition coil assembly of FIG. 1.

The components of the display shown in broken lines illustrate portions of the motorcycle ignition coil assembly which form no part of the claimed design.
